UNITED STATES PATENT OFFICE.

JOHN W. POST, OF NEW YORK, N. Y.

SEWING-MACHINE.

SPECIFICATION forming part of Letters Patent No. 312,509, dated February 17, 1885.

Application filed July 14, 1883. (No model.)

To all whom it may concern:

Be it known that I, JOHN W. POST, a citizen of the United States, residing at New York, in the county of New York and State 5 of New York, have invented certain new and useful Improvements in Sewing-Machines, of which the following is a specification, reference being had therein to the accompanying drawings.

10. The object of my invention is the production of a sewing-machine which, while it is so simple in construction that it may be sold at the price usually asked for what are known as "toy" sewing-machines, is so efficient in 15 operation that it will sew as well as many of the high-priced "family" sewing-machines.

In the accompanying drawings, Figure 1 is 20 a sectional side elevation of a sewing-machine embodying my invention. Fig. 2 is a reverse plan view of the same. Fig. 3 is a front elevation with the bed-plate in section. Fig. 4 is a sectional view of the head and a portion 25 of the bracket-arm. Fig. 5 is a sectional detail of the needle-lever and its bearing, and Fig. 6 is a perspective detail of the tension device.

A is the bed-plate, to which is secured the bracket-arm B, the latter being formed solid and in one piece, the head C of said bracket-arm being preferably formed integral therewith, as shown.

Cast integral with the bed-plate A are small legs a and lugs a' , the latter affording bearings for the driving-shaft D, which is preferably cast in one piece with the fly-wheel D', having a driving-pulley, d, and the needle-operating eccentric D².

On the forward end of the driving-shaft is 40 formed an eccentric, D², for operating the feed-bar E, the latter carrying a feed-dog, E', of ordinary construction. The eccentric D² works in a slot in said feed-bar in a well-known manner, and moves the same forward in opposition to the stress of a coiled spring arranged 45 in a recess in said bar and against the pin on which the latter is pivoted. The throw of the feed-bar is regulated by an adjusting-lever, E².

To the forward end of the driving-shaft a 50 rotary chain-stitch hook or looper, F, is secured in a well-known manner.

In the head C of the bracket-arm are formed vertical bearings for the needle-bar G; carry-

ing the usual eye-pointed needle, g, and the presser-bar H, having a presser-foot, h, of ordinary construction, said presser-foot being 55 yieldingly held upon the work by a coiled spring, h², encircling the presser-bar, and the latter being raised, when required, by a lifting-lever, h⁴. The needle-bar G receives its movement from the eccentric D² on the driving-shaft through the connecting-rod I and needle-lever J, the latter being provided at its rear end with a ball, j, which is surrounded by a yoke, i, on the upper end of the connecting-rod. To prevent said yoke from coming off from said ball, a set-screw, i², is passed 60 through the former into a seat or recess, j', in the latter, as clearly shown in Fig. 5. The forward end of the needle-lever is provided with a fork embracing a screw-pin, g², on the needle-bar, the prongs of the fork being adjusted to take up wear by a screw, j², passing through the same. The needle-lever J is pivoted on a stud or pin, J², preferably formed 65 conical and integral with said needle-lever, as shown in Fig. 5, said pin fitting in a conical bearing in the bracket-arm B, and being held in said bearing by a screw, J³. As the pin or stud J² is slightly shorter than the bearing in the bracket-arm, it is obvious that any wear 70 of the said stud J² or its bearing may be compensated for simply by tightening the screw J³.

By arranging the adjusting-screw J³ at the back of the bracket-arm, or on the side of the said arm opposite to that on which the needle-lever is placed, a projecting nut or screw-head on the front of the machine is avoided, thus giving this part of the machine a neat and smooth front.

The tension device consists of a spring, K, 90 secured to the top of the bracket-arm B by a single screw, K², by which the stress of said spring may be adjusted. The rear end of the tension-spring K is bent at a right angle, the lower end of the vertical portion of said rear end being preferably formed with a concave seat fitting on the round bracket-arm. The forward end of the tension-spring K bears on the top of the head C, the thread being passed between said spring and the upper surface of 95 said head. A supplementary or check tension-spring, L, is secured to the front of the head C by a single screw, l², by which the stress of said spring may be adjusted, the free end of 100

said spring L being steadied between two pins, l l, preferably arranged in different vertical planes, as shown in Fig. 3, so that they will serve as guides for the thread, which passes between them beneath the spring L. A wire loop, g³, secured to the upper end of the needle-bar G, serves as a take-up to tighten the stitches.

To prevent the needle and presser bars from turning in their bearings, the head C is provided with a slot, c, into which the ends of the screw-pins g² and h³, passing through the needle and presser bars, respectively, project. One wall of this slot is preferably formed by a removable plate, c², secured to the head by screws c³.

It is obvious that any wear of the pins g² and h³ in the slot c may be compensated for by tightening the screws c³, thus enabling a single adjustable device to take up the wear of both of these pins. The thread passes from the spool M between the outer end of the tension-spring K² and the upper surface of the head C, thus receiving its requisite tension. From the tension-spring the thread passes through the take-up loop g³, thence beneath the check tension-spring L and through the guide-eye N to the eye of the needle.

If it is desired to drive my machine by hand, a driving-pulley, D⁴, (indicated by dotted lines in Fig. 1,) provided with a handle, may be secured to the rear end of the bracket-arm B by a screw, D⁵, entering a threaded socket, b, Fig. 5, in said arm. A belt will run from the pulley D⁴ to the pulley d on the driving-shaft.

As the operation of my machine in sewing is essentially the same as that of the well-known Willcox & Gibbs chain-stitch machine, it will be fully understood by those skilled in the art without further description.

I do not herein claim the tension devices

above described, as this part of my invention is embraced by my application, Serial No. 153,652, filed January 22, 1885, which is a division of this application.

45

Having thus described my invention, I claim as new and desire to secure by Letters Patent—

1. In a sewing-machine, the combination, with a bracket-arm having a conical bearing, of a needle-lever having a conical fulcrum-stud 50 formed integral therewith, said stud being slightly shorter than said bearing, and means arranged on the side of said bracket-arm opposite to the said lever for securing and adjusting said stud in said bearing, substantially as described.

2. The bracket-arm B, provided with a conical bearing, in combination with the needle-lever J, having a conical fulcrum-stud, J², formed integral with said lever, said stud being slightly shorter than said bearing, and the securing and adjusting screw J³, arranged on the side of said bracket-arm opposite to the said lever, substantially as described.

3. The combination, with the head C, having a slot, of the needle and presser bars provided with pins entering said slot, and a single and adjustable device for compensating for the wear of said pins in said slot, substantially as described.

4. The combination, with the head C, having the slot c, of the needle and presser bars having pins entering said slot, and the adjustable and removable plate c², substantially as and for the purposes set forth.

In testimony whereof I affix my signature in presence of two witnesses.

JOHN W. POST.
